UNITED STATES PATENT OFFICE.

CHARLES E. POTTER, OF WILKES-BARRE, PENNSYLVANIA.

CLARINET.

Application filed January 9, 1926. Serial No. 80,206.

The principal object of the invention is to provide improvements for a clarinet of standard design whereby certain lower register notes which have heretofore always been sharp are flattened or lowered to the proper pitch, and whereby certain upper register notes which have heretofore been flat are sharpened or raised to the proper pitch.

More specifically the object of the invention is to provide reductions in the sizes of certain holes, together with corresponding additional holes and also means for opening and closing the additional holes whereby the beforementioned results are obtained.

A further object of the invention is to provide a certain specific mechanism for opening and closing the beforementioned additional holes.

Still further objects of the invention will be apparent from the following specification and claims.

In the accompanying drawings, I have shown the embodiment of the invention which I now deem preferable, but it will be understood that the drawings are for illustrative purposes only and are not to be construed as defining or limiting the scope of the invention, the claims forming a part of this specification being relied upon for that purpose.

Of the drawings:

Figs. 1 and 2 are musical diagrams showing the notes which are corrected and restored to the proper pitch in accordance with the invention.

Figs. 3 and 4 are fragmentary side views of a clarinet, the views being taken from different angles.

Figs. 5 to 7 are enlarged transverse sectional views taken respectively along the lines 5—5, 6—6, and 7—7 of Fig. 4.

Figs. 8 and 9 are views similar to Fig. 7, but showing the parts in different relative positions.

Fig. 10 is an enlarged transverse sectional view taken along the line 10—10 of Fig. 4.

Fig. 11 is a fragmentary detail view partly in section along the line 11—11 of Fig. 7.

Fig. 12 is a fragmentary detail view partly in section along the line 12—12 of Fig. 7.

Fig. 13 is an enlarged perspective view showing a detail.

Fig. 14 is an enlarged fragmentary side

view, this view being taken in the direction of the arrow 14 in Fig. 7.

Fig. 15 is an enlarged perspective view shown in detail.

It is a recognized fact that in all clarinets 60 certain notes in the lower register are sharp, these ordinarily being the notes A, A#, B, C, C# and D as shown in Fig. 1. Certain notes in the upper register are flat, these notes being E, F, F#, G, G#, A, C#, D, D#, 65 E, F and F# as shown in Fig. 2. In standard clarinets compromise tones are determined upon so as to prevent the lower register notes from being excessively sharp and so as to prevent the upper register notes 70 from being excessively flat. Prior to my invention, there has been no known means or method for lowering the lower register notes to the proper pitch without, at the same time, lowering the upper register notes 75 to such an extent that they would be exceedingly flat and discordant. Conversely there has been no known means or method whereby the upper register notes could be raised to the proper pitch without at the 80 same time making the lower register notes excessively sharp and discordant. In accordance with the present invention, all of these notes are brought to the proper pitch 85 thus providing for the first time a clarinet 85 which is absolutely in tune throughout its entire range.

The invention is not limited to a clarinet of any particular type, but, by way of example, I have illustrated it as applied to a clarinet of the well known Boehm model. The standard operative parts of a Boehm clarinet are illustrated in Figs. 3 and 4, but inasmuch as the standard parts of the instrument are well known and are not of 95 themselves involved in the invention, a detailed description thereof will be omitted.

In order to properly flatten the lower register notes, particularly those referred to, the holes 1, 2 and 3, which are ordinarily 100 opened and closed by the first, second and third fingers respectively of the right hand, are made somewhat smaller than standard, the reduction in the cross-sectional area of these holes being just sufficient to flatten 105 the lower register notes and lower them to the proper pitch.

As already suggested the lowering of the pitch of the lower register notes would (if nothing else were done) lower the pitch 110

of the upper register notes to such an extent that they would be excessively flat. In accordance with my invention, I avoid this flattening of the upper register notes by 5 providing one or more additional holes in the clarinet, together with devices for opening and closing them. When the lower register notes are being played the holes are normally closed, and provision is made 10 for opening these holes when the upper register notes are being played. I do not limit myself to any particular number of holes or to any exact location thereof, but I prefer to provide and have shown three 15 holes 4, 5 and 6, together with tampions 7, 8 and 9 respectively adapted to close the holes. A single means is provided for moving the tampions 7, 8 and 9 to open positions and preferably this means is so constructed that it is automatically operated whenever the upper register key 10 is operated. 20

The total area of the three holes 4, 5 and 6 is such as to at least compensate for the 25 reduction in area of the three holes 1, 2 and 3. However, inasmuch as some of the upper register notes are ordinarily flat, the area of the holes 4, 5 and 6 is preferably sufficient not only to compensate for the 30 reduction in the holes 1, 2 and 3 but also to correct the flatness which already existed in the upper register notes. 35

It will be obvious that the entire additional cross-sectional area of the holes 4, 5 and 6 is needed only when all three of the holes 1, 2 and 3 are open. In order to maintain the various upper register notes at the proper pitch, it is necessary to close one or more of the holes 4, 5 and 6 when one or 40 more of the corresponding holes 1, 2 and 3 are closed. It will thus be seen that I primarily provide means for increasing the total area of opening when notes in the upper register are being played, and that with 45 this I combine means whereby the additional area can be again reduced as one or more of the holes 1, 2 and 3 are closed. 50

As concerns the specific mechanism which is used to accomplish the results which I have described, there can be wide variation 55 within the scope of my invention. However, in order that the invention may be clearly understood, I have shown in the drawings, and will now describe in detail the specific mechanism which I have found preferable and which will form the basis of some of the more specific claims of this application. 60

The three tampions 7, 8 and 9 are all 65 loosely mounted on a bearing shaft 11 which is rotatably mounted on pivot screws 12, 12 carried by studs 13, 13 projecting from the body of the clarinet. These parts are most clearly shown in Figs. 7, 8, 9 and 12. Spring wires 14 and 15 are provided which 65

engage lugs 16, 16 on the sleeves of the respective tampions, these spring wires acting in the direction to hold the tampions in their open positions. Pinned or otherwise secured to the shaft 11 are hubs 17, 17 which are 70 provided with adjustable screws 18, 18. These screws are adapted to engage lugs 19, 19 projecting laterally from the respective tampions. It will be seen that when the shaft 11 is rotated in the counterclockwise 75 direction, as viewed in Fig. 7, the tampions will all be moved to closed positions in opposition to the action of the springs 14 and 15. For moving the shaft 11 in the counterclockwise direction, there is provided a 80 spring 20 which engages a pin 21 carried by one of the hubs 17, as shown in Fig. 16. This spring 20 is of sufficient strength to overcome the combined action of the springs 14 and 15, the result being that the tampions 85 are normally held in closed positions notwithstanding the tendency of the springs 14 and 15 to move them to open positions. Fig. 7 shows one of the tampions in its normal closed position. 90

Suitable means is provided for turning the shaft 11 in the clockwise direction and in opposition to the spring 20 for the purpose of permitting the tampions 7, 8 and 9 to open under the action of the springs 14 and 15. Preferably this means is connected to be actuated automatically by the before-mentioned upper register key 10. As illustrated a bearing shaft 22 is provided, this being suitably mounted on studs 23, 23 on 100 the body of the upper section A of the clarinet. Rotatably mounted on the shaft 22 is a sleeve 24 carrying a lever 25 at the end adjacent the upper register key 10. At the other end the sleeve carries a lever 26 which 105 is provided with a projection 27 extending under a projection 28 on a lever 29 secured to the shaft 11. It will be seen that when the sleeve 24 is turned in the clockwise direction the shaft 11 will be turned in the same 110 direction. The engagement of the two projections 27 and 28 on the levers 26 and 29 permits the upper section A of the clarinet to be separated from the lower section B in the usual way. 115

Pivotedly mounted on the body of the section A of the clarinet is a lever 20 which projects between the upper register key 10 and the body at one end and which has engagement at the other end with the before-mentioned lever 25. The result is that when the key 10 is pressed to adapt the clarinet for playing upper register notes the sleeve 24 is turned in the clockwise direction thus simultaneously turning the shaft 11 in the 120 clockwise direction and permitting the tampions 7, 8, and 9 to open as already described. Each tampion is thus moved from the position shown in Fig. 7 to the position shown in Fig. 8. 125 130

I have already stated that the full additional area of the holes 4, 5 and 6 is needed only when all of the holes 1, 2 and 3 are open. When any one of the holes 1, 2 and 3 is closed the corresponding hole 4, 5 or 6 should be closed. In order that the holes 4, 5 and 6 may be thus closed automatically, I provide the mechanism which will now be described.

- 10 Respectively associated with the holes 1, 2 and 3 are rings 31, 32 and 33, these rings being similar to those ordinarily provided on clarinets. Associated with the rings 31, 32 and 33 is a tampion 34 which must be moved to closed position when any one of the holes 1, 2 or 3 is closed. In standard clarinets all of the rings 31, 32 and 33 are mounted on a single shaft which is connected with the tampion 34 so that the tampion 20 is moved to closed position when any one of the rings is engaged by a finger moving to close a hole. I obtain a similar result, but use a mechanism which is constructed somewhat differently for a purpose which will 25 presently appear.

As illustrated most clearly in Fig. 11 the tampion 34 is carried by a shaft 35 supported on pivot screws 36, 36 carried by studs 37, 37. The rings 31, 32 and 33 are carried respectively on sleeves 38, 39 and 40, all loosely mounted on the shaft 35. Each of the sleeves carries a lug 41 which is engaged by a spring (not shown), the spring tending to hold the ring away from the body as shown in Figs. 7 and 8. Secured to the shaft 35 are hubs 42 and 43. The hub 42 has a projection adapted to be engaged by a screw 44 carried by the ring 31 and the hub 43 has a broader projection adapted to be engaged by a screw 45 carried by the ring 32, and also by a screw 46 carried by the ring 33. By reason of the construction described, the tampion 34 is moved to closed position when any one of the rings 31, 32 and 33 is moved inward. By reason of the independent mounting of the rings no ring is moved by any other ring.

Carried respectively by the sleeves 38, 39 and 40 are arms 47, 48 and 49 which are adapted to respectively engage screws 50, 51 and 52 carried respectively by arms formed on the tampions 7, 8 and 9. It will be recalled that the tampions 7, 8 and 9 are held in their open positions as shown in Fig. 8 solely by the action of the springs 14 and 15, and that each of them is therefore free to be moved to its closed position in opposition to the action of the corresponding spring. The movements of the respective tampions to closed positions, as shown in Fig. 9, are effected by means of the arms 47, 48 and 49 associated with the rings 31, 32 and 33 as already described. From the description, it will be clear that when the player moves his finger to close any one of

the holes 1, 2 or 3 he engages the corresponding ring 31, 32 or 33 and by reason of the movement of the ring closes the corresponding hole 4, 5 or 6.

The hole 53 which is ordinarily located at the position 53^a shown in dotted lines in Fig. 10 is preferably shifted to the position shown in full lines. This is done for purely mechanical reasons to avoid interference with the tampions 7, 8 and 9 and the operating mechanism therefor. The tampion 54 for the hole 53 has its key 55 located at the same position as the corresponding key of the standard clarinet.

It will be clearly apparent from the foregoing description that I have accomplished the results described without in any way modifying the fingering of the instrument. I have provided no additional keys, and the additional holes which are provided require no special attention on the part of the player. The inaccuracies of tone which have heretofore existed have been corrected, but the player of the clarinet has nothing new to learn.

I claim:

1. A clarinet having certain holes smaller than standard, whereby the usual sharpness of certain lower register notes is eliminated, and also having additional holes of such area as to compensate for the reduction in area of the first said holes, in combination with manually operable means for closing the additional holes when notes of the lower register are to be played, and means for opening them only when notes of the upper register are to be played.

2. A clarinet having certain holes smaller than standard, whereby the usual sharpness of certain lower register notes is eliminated, and also having additional holes of such area that the usual flatness of the upper register notes is avoided, in combination with manually operable means for closing the additional holes when notes of the lower register are to be played.

3. A clarinet having certain holes smaller than standard, whereby the usual sharpness of certain lower register notes is eliminated, and also having additional holes of such area that any flatness of the upper register notes is avoided, in combination with manually operable means for closing the additional holes when notes of the lower register are to be played and for opening any one or more of them only when notes of the upper register are to be played.

4. A clarinet having certain holes smaller than standard, whereby the usual sharpness of certain lower register notes is eliminated, and also having additional holes of such area that any flatness of the upper register notes is avoided, in combination with manually operable means for closing the additional holes when notes of the lower

register are to be played and for opening any one or more of them when notes of the upper register are to be played, and means associated with the first said holes for controlling the opening of the said additional holes.

5. A clarinet having certain holes smaller than standard, whereby the usual sharpness of certain lower register notes is eliminated, 10 and also having additional holes of such area that any flatness of the upper register notes is avoided, in combination with devices for closing the additional holes when notes of the lower register are to be 15 played, and means operable by the upper register key of the clarinet for moving the said devices to open the said additional holes.

6. A clarinet having certain holes smaller 20 than standard, whereby the usual sharpness of certain lower register notes is eliminated, and also having additional holes of such area that any flatness of the upper register notes is avoided, in combination with devices for closing the additional holes when 25 notes of the lower register are to be played, means operable by the upper register key of the clarinet for moving the said devices to open any one or more of the said additional 30 holes, and means associated with the first said holes for controlling the movements of the said devices to open positions.

7. A clarinet having certain holes smaller 35 than standard, whereby the usual sharpness of certain lower register notes is eliminated, and also having additional holes corresponding in number to the first said holes and of such area that any flatness of the upper register notes is avoided, in combination with 40 devices for closing the additional holes when notes of the lower register are to be played, means operable by the upper register key of the clarinet and normally serving to move all of the said devices to open 45 the said additional holes, and means associated with the first said holes for respectively moving the said devices to closed po-

sitions or for preventing their movement to open positions.

8. A clarinet having certain holes smaller 50 than standard, whereby the usual sharpness of certain lower register notes is eliminated, and also having additional holes of such area that any flatness of the upper register notes is avoided, in combination with devices for closing the additional holes when 55 notes of the lower register are to be played, springs tending to move each of the said devices to open position, a spring acting on all of the devices and serving to move them 60 to closed positions in opposition to the first said springs, means operable by the upper register key of the clarinet for overcoming the last said spring to permit the said devices to be moved to open positions by the 65 first said springs, and means including rings associated with the first said holes for moving the said devices to closed positions or for preventing their movement to open positions. 70

9. A clarinet having certain holes smaller than standard, whereby the usual sharpness of certain lower register notes is eliminated, and also having additional holes of such area that any flatness of the upper register 75 notes is avoided, in combination with devices for closing the additional holes when notes of the lower register are to be played, springs tending to move each of the said devices to open position, a spring acting on all 80 of the devices and serving to move them to closed positions in opposition to the first said springs, means operable by the upper register key of the clarinet for overcoming the last said spring to permit the said devices to be moved to open positions by the 85 first said springs, and means including rings associated with the first said holes and independently movable for respectively moving the said devices to closed positions or for preventing their movements to open positions. 90

CHARLES E. POTTER.
